BOTTLE CARRIER WITH REINFORCED HANDLE AND METHOD OF MAKING IT

Robert M. Bergstein, Wyoming, Ohio, assignor to The Bergstein Packaging Trust, a trust composed of Robert M. Bergstein and Frank D. Bergstein

Application June 14, 1952, Serial No. 293,530

5 Claims. (Cl. 220—113)

My invention relates to paperboard bottle carriers and more particularly to knock-down or flat-folding carriers having internal partition structures to effectively divide a plurality of bottles or containers placed in the carrier.

In my copending application entitled Fully Partitioned Collapsible Bottle Carrier, Serial No. 273,896, filed February 28, 1952, now Patent No. 2,731,170, I have taught the provision of a fully partitioned carrier of exceptional strength, in which the partition elements are formed as an integral part of the carrier and are erected automatically to the desired position as the body walls of the carrier are erected. In the field of such carriers, it has become increasingly important to provide exceptionally strong carrying handles for the carriers, which handles will be strong enough to support the full load of the carriers for a long period of time under conditions wherein the boxboard of the carrier is unusually damp or even wet due to absorption into the boxboard of unusually large amounts of moisture vapor, as occasioned by the storage of the carriers in a refrigerator or ice house, as has now become customary, or due to the direct exposures of the carriers to water in the form of rain or otherwise.

A number of bottlers throughout the country have set up testing standards to determine the serviceability and strength characteristics of carriers submitted for approval for use with their products. One of the standard tests is to expose the test carriers to a shower of water, then apply a predetermined weight load to them, while holding the carriers by their handles, to determine the weight load which the carrier will support even when wet. A similar test, known as a dry test, which eliminates the water shower is also employed; and it has been found that a large number of carriers which will satisfactorily pass the dry test, fail to pass the wet test. This failure in a great many instances is due to the lack of adequate strength in the handle parts of the carriers and the tendency of the board to tear in the areas immediately above the hand hole openings and adjacent the ends thereof.

It is, therefore, a principal object of my invention to provide a paperboard carrier construction having an extremely sturdy, reinforced handle. It is a further object of my invention to provide a sturdy, reinforced handle in a one piece knock-down carrier structure without increasing the amount of board needed to manufacture the same carton structure without the reinforced handle.

Yet another object of my invention is the provision of a carrier structure having a reinforced handle the parts of which can be folded and glued on equipment currently available in the industry without the need of expensive modifications or major alterations to the equipment.

These and other objects of my invention which will appear hereinafter or will be apparent to the skilled worker in the art upon reading these specifications, I accomplish by those constructions, procedures and ar-

2

rangements of parts of which I shall now describe certain exemplary embodiments:

Reference is now made to the accompanying drawings wherein:

5 Figure 1 is a plan view of the blank for my carrier.

Figure 2 is a plan view of the blank of Figure 1 illustrating an intermediate step in its assembly.

Figure 3 is a sectional view taken along the line 3—3 of Figure 1.

10 Figure 4 is a sectional view similar to Figure 3 illustrating one mode of infolding the handle reinforcing portions.

Figure 5 is a sectional view similar to Figure 4 illustrating the completion of the folding of the handle reinforcing portions of Figure 4.

15 Figures 6 and 7 are sectional views similar to Figure 3 illustrating an alternative mode of infolding the handle reinforcing portions.

Figure 8 is a plan view similar to Figure 2 illustrating 20 the next stage in the assembly of the carrier structure.

Figure 9 is a sectional view taken along the line 9—9 of Figure 8.

Figure 10 is a plan view similar to Figure 8 illustrating 25 the carrier in the completely assembled but knocked-down condition.

Figure 11 is a sectional view taken along the line 11—11 of Figure 10.

Figure 12 is a vertical sectional view taken through the 30 center of the fully erected carrier.

Figure 13 is a partial sectional view similar to Figure 12 illustrating the hand hole flaps in carrying position.

Figure 14 is a view similar to Figure 13 illustrating a 35 modified handle construction.

Referring now to Figure 1 of the drawings, the carrier blank comprises a bottom panel 1 divided in half by medial score line 2, with side wall panels 3 and 4 articulated to opposite side edges of the bottom panel. Partial

40 end wall panels 5, 6, 7 and 8 are articulated to opposite side edges of the side wall panels and attachment flaps 9 and 10 are articulated to the outer side edges of partial end wall panels 5 and 7 respectively. Handle forming parts 11 and 12, and transverse partition parts 13, 14, 15 and 16 are provided, as illustrated. Attachment flaps 17 and 18 are articulated both to the partial end wall

45 panels 6 and 8 and to handle forming parts 11 and 12, and end tabs 19 and 20 are articulated both to handle-forming parts 11 and 12 and to end wall portions 5 and 7. Pairs of hand-hole opening tabs 21 and 22, and 23 and 24 are provided in the handle forming parts 11 and 12, respectively. Of course, single, elongated hand-hole 50 opening may be provided if desired.

55 A center partition and handle-forming part 25 is articulated to the free edge of handle forming part 12 along score line 26. Handle reinforcing portions 27 and 28 are formed in the handle-forming part 25, the portion 27 being articulated to the handle part along the score line 29 with the handle reinforcing portion 28 articulated to portion 27 along score line 30. The reinforcing portions are preferably longer than the overall length of the hand-hole openings so as to project beyond the ends of the hand-hole openings in the assembled carrier.

60 The configuration of the carrier blank is such that pairs of blanks may be nested with respect to each other by placing them end to end with the extending center partition panels 25 parallel to each other for the utmost possible conservation of boxboard.

65 In assembling the blank of Figure 1 into a flat-folded carrier structure, the blank may be folded by hand; but preferably it is folded and glued employing suitable folding and gluing equipment which forms no part of my invention. The construction of the blank is such that it may be folded and glued on a straight line gluer, such

as a Staude master gluer, or it may be folded and glued in a right angle folding and gluing machine of the type found in the average box making plant. As seen in Figure 2, the first folding operation results in the infolding of partial end wall panels 5 and 7 along the lines of articulation between the said end wall panels and side walls 3 and 4, together with the infolding of the attachment flaps 17 and 18 to overlie partial end wall panels 6 and 8.

Handle reinforcing portions 27 and 28 are then infolded to the position illustrated in Figure 2. Adhesive may be applied to the reinforcing portions before folding, as indicated by the shaded area in Figure 1 of the drawings, or the adhesive may be applied to the portions of the blank which the infolded reinforcing portions overlie rather than to the reinforcing portions themselves; and I have also found that the adhesive for the reinforcing portions may be omitted entirely and the reinforcing portions maintained in folded condition by the subsequent folding and gluing of the handle parts.

The folding of the handle reinforcing portion 27 and 28 may be effected, as seen in Figures 3, 4 and 5, by means of a spring finger 31 which will act to force the reinforcing portions upwardly, as seen in Figure 4. As the reinforcing portions are forced upwardly, a sword 32 will engage the reinforcing portions and fold them over and down until the position illustrated in Figure 5 is reached.

In Figures 6 and 7 of the drawings, I have illustrated an alternative mode of folding the reinforcing portions wherein a spring finger 31a buckles the portions 27 and 28 with respect to each other along score line 39, whereupon a sword 32a engages the upper surface of reinforcing portion 28 and enforces the folding of the portions to the condition illustrated in Figure 7.

Following the infolding of the reinforcing portions, the center partition panel 25 is next infolded to overlie the handle forming part 12 and attachment flaps 10 and 18, adhesive having been previously applied to attachment flaps 10 and 18 as indicated by the shaded areas in Figure 2. For this and subsequent folding operations the blank will be moving in the direction indicated by the arrow A, (Figure 8) irrespective of whether the carrier is being formed on straight line or right angle folding and gluing equipment. Where the handle reinforcing portions 27 and 29 are infolded in the manner illustrated in Figures 3, 4 and 5, it will be noted that the score line 30 separating the reinforcing portions 27 and 28 coincides with the score line 26 between handle-forming part 12 and center partition panel 25; and upon the subsequent infolding of center partition panel 25, the reinforcing portions 27 and 28 will be juxtaposed and both portions will overlie the portion of handle-forming part 12 lying above the hand hole tabs 23 and 24, as can be best seen in Figure 9 of the drawings. The folding step just described can be characterized as one in which the handle parts are folded inner surface to inner surface whereas the reinforcing panels are folded outer surface to outer surface. For the infolding of these parts, the sword 32 can be used as a scorebreaker for the coinciding score lines 26 and 30.

Next the blank is folded along the median score line 2 to bring handle-forming part 11 and attachment flaps 9 and 17 into contact with the center partition panel 25 and the exposed end portions of attachment flaps 10 and 18. Prior to the infolding of these parts, adhesive will be preferably applied to the parts as indicated by the shaded areas in Figure 8 of the drawings. The flat-folded form of the carrier is seen in Figures 10 and 11, the latter figure clearly illustrating the 5-ply reinforced handle formed by this construction.

In its flat-folded form the carrier is ready to be shipped to the user who has only to erect the structure from the flat-folded condition to ready it for use. The erected

carrier is seen in Figure 12; and in Figure 13 the handle of the carrier is shown with the hand hole tabs, such as the tabs 22 and 24, folded to expose the hand hole openings, the undermost tab 22 passing through the opening from one side to the other to form a smooth gripping surface.

It will be evident from the preceding description that my construction provides an exceedingly strong carrier structure having a 5-ply reinforced handle. The handle reinforcing portions, being longer than the hand-hole opening, serve to reinforce the handle structure adjacent and beyond the ends of the hand-hole openings where tearing of the handles is most likely to occur. In addition to reinforcing the handle of the carrier, my construction provides for increased reinforcement down opposite sides of the carrier, the multiple plies formed by the attachment flaps, such as the flaps 17 and 18, the center partition panel 35 and the handle forming parts 11 and 12, acting to greatly strengthen and rigidify the carrier structure, thereby preventing buckling and other distortion of the parts which would interfere with the automatic machinery now employed both to load and unload the carriers.

Modifications may be made in my invention without departing from the spirit of it. For example, as seen in Figure 14 of the drawings, it is within the spirit of my invention to eliminate reinforcing portion 28 leaving only reinforcing portion 27, which, when infolded, provides a 4-thickness handle structure. It will be evident also that modifications may be made in the manner in which adhesive is applied to the various parts; and it will also be evident that my reinforced handle construction will have application in carrier structures other than the exemplary embodiment described herein.

However, having described my invention in an exemplary embodiment, what I desire to protect and secure by Letters Patent is:

1. In a reinforced handle construction for paperboard carriers and the like, a first handle part, a hand-hole opening in said handle part spaced from the upper edge thereof, a second handle part articulated to the upper edge of said first handle part and foldable relative thereto, a reinforcing panel formed in said second handle part and articulated thereto along a line of articulation spaced from the line of articulation connecting said first and second handle parts by a distance substantially equal to the distance between said last named line of articulation and the hand-hole opening in said first handle part, said reinforcing panel having a length greater than the length of the hand-hole opening in said first handle part and scored in the direction of the length thereof to define two reinforcing portions each having a width substantially equal to the distance between the line of articulation connecting said handle parts and the line of articulation joining said reinforcing panel to said second handle part, said handle parts lying in face-to-face relation with said reinforcing portions folded with respect to each other and with respect to said second handle part and juxtaposed between said first and second handle parts above the hand-hole openings defined therein.

2. In a reinforced handle construction for paperboard carriers and the like, a first handle part, a hand-hole opening in said handle part spaced from the upper edge thereof, a second handle part articulated to the upper edge of said first handle part and foldable relative thereto, a reinforcing panel formed in said second handle part and articulated thereto along a line of articulation spaced from the line of articulation connecting said first and second handle parts by a distance substantially equal to the distance between said last named line of articulation and the hand-hole opening in said first handle part, said reinforcing panel having a length greater than the length of the hand-hole opening in said first handle part and scored in the direction of the length thereof to define

two reinforcing portions each having a width substantially equal to the distance between the line of articulation connecting said handle parts and the line of articulation joining said reinforcing panel to said second handle part, said handle parts lying in face-to-face relation with said reinforcing portions folded with respect to each other and with respect to said second handle part and juxtaposed between said first and second handle parts above the hand-hole openings defined therein, one of said reinforcing portions being adhesively secured to the inner surface of said first handle part and the other of said reinforcing portions being adhesively secured to the inner surface of the other of said handle parts.

3. In a reinforced handle construction for paperboard carriers and the like, a first handle part, a hand-hole opening in said handle part spaced from the upper edge thereof, a second handle part articulated to the upper edge of said first handle part and foldable relative thereto, a reinforcing panel formed in said second handle part and articulated thereto along a line of articulation spaced from the line of articulation connecting said first and second handle parts by a distance substantially equal to the distance between said last named line of articulation and the hand-hole opening in said first handle part, said reinforcing panel having a length greater than the length of the hand-hole opening in said first handle part and scored in the direction of the length thereof to define two reinforcing portions each having a width substantially equal to the distance between the line of articulation connecting said handle parts and the line of articulation joining said reinforcing panel to said second handle part, said handle parts lying in face-to-face relation with said reinforcing portions folded with respect to each other and with respect to said second handle part and juxtaposed between said first and second handle parts above the hand-hole openings defined therein, and a third handle part adhesively secured to said second handle part in face-to-face contacting relationship, said third handle part having a hand-hole opening therein corresponding in length to the hand-hole opening in said first handle part.

4. A process of producing a reinforced handle structure for paperboard carriers and the like which comprises providing a blank including a first handle part, a hand-hole opening in said handle part spaced from the upper edge thereof, a second handle part articulated to the upper edge of said first handle part, a reinforcing panel formed in said second handle part and connected thereto along a line of articulation spaced from the line of articulation connecting said first and second handle parts by a distance substantially equal to the distance between said last named line of articulation and the hand-hole opening in said first handle part, said reinforcing panel being scored in the direction of the length thereof to define two

reinforcing portions each having a width substantially equal to the distance between the line of articulation connecting said handle parts and the line of articulation joining said reinforcing panel to said second handle part, folding said handle reinforcing portions so as to bring the reinforcing portion adjacent said last named line of articulation into face-to-face contact with said second handle part, and thereafter folding said handle parts with respect to each other so as to juxtapose the other of said reinforcing portions between said first handle part and the first of said reinforcing portions.

5. A process of producing a reinforced handle structure for paperboard carriers and the like which comprises providing a blank including a first handle part, a hand-hole opening in said handle part spaced from the upper edge thereof, a second handle part articulated to the upper edge of said first handle part, a reinforcing panel formed in said second handle part and connected thereto along a line of articulation spaced from the line of articulation connecting said first and second handle parts by a distance substantially equal to the distance between said last named line of articulation and the hand-hole opening in said first handle part, said reinforcing panel being scored in the direction of the length thereof to define two reinforcing portions each having a width substantially equal to the distance between the line of articulation connecting said handle parts and the line of articulation joining said reinforcing panel to said second handle part, folding said handle reinforcing portions along the line of articulation to said second handle part so as to bring the first of said reinforcing portions into face-to-face contact with said second handle part and the other of said reinforcing portions into face-to-face contact with said first handle part, with the line of articulation between said reinforcing portions coinciding with the line of articulation between the said handle parts, and thereafter folding said handle parts with respect to each other so as to juxtapose the reinforcing portions with respect to each other, including the step of interposing adhesive between said reinforcing portions and the portions of the handle parts which they contact.
